C. T. APPLETON.
DYEING.

No. 10,664.

Patented Mar. 21, 1854.

UNITED STATES PATENT OFFICE.

CHARLES T. APPLETON, OF ROXBURY, MASSACHUSETTS.

PROCESS FOR DYEING.

Specification of Letters Patent No. 10,664, dated March 21, 1854.

To all whom it may concern:

Be it known that I, CHARLES T. APPLETON, of Roxbury, in the county of Norfolk and Commonwealth of Massachusetts, have invented certain new and useful Improvements in the Art of Dyeing; and I hereby declare the following to be a full, clear, and exact description of the same, reference being had to the annexed drawings, making 10 part of this specification, in which—

Figure 1 is a view of the machinery of which I make use, showing the method by which it is actuated; Fig. 2, a section through the same, and Fig. 3 a view of the 15 parts which communicate the alternate rotary motion to the rollers.

In the machines now used in dyeing the goods having been stitched together, are run in one direction over rollers immersed 20 in a vat containing dyeing liquor. For certain colors which take very readily to the cloth or the mordants with which it has been saturated, this process is found effectual and cheap, but experience has proved 25 that many colors cannot be put on uniformly and with exactness by these machines, and for such the dyer has been obliged to resort to hand dyeing, in which process, the goods having been stitched together, eight 30 or ten pieces are wound or reeled by the operative for their entire length through a tub or vat of dyeing liquor, and this operation is often many times repeated before the required shade of color is attained.

In my invention the vat and rollers used 35 are similar to the machines now in use (except that the rollers being smaller more cloth is contained in the vat) but the motion instead of being in one direction is reciprocal. The rollers are alternately rotated in one direction and the opposite carrying the cloth only a few feet in each direction in such a manner that the whole fabric is immersed in the dyeing liquor several 40 times in each minute, and either the cloth or the liquor may be instantaneously withdrawn from the other, whenever the exact shade of color is attained. By this method every particle of coloring matter 45 contained in the vat may be distributed with perfect uniformity over the whole fabric. If it is insufficient it may be added to; if it is in excess, it may be withdrawn and saved. By the alternate motion, the dyer 50 is enabled to subject his goods for any length of time to the action of the dyeing liquor,

that may be required for the kind of color or the depth of shade to be produced, while, by a motion in one direction the speed of the machine would have to be differently adjusted to every variety of color and shade wanted, and the first pieces in a series of goods passing slowly through the vat would absorb the coloring matter, making a deficiency for those which followed.

To enable others skilled in the art to make and use my invention I will proceed to describe the method in which I have carried it out.

A' is the vat which contains the dyeing liquor; B', a strong frame of suitable material fitting closely within the vat, but which may at any time be withdrawn therefrom. In the upper bars of this frame run the rollers a' a'' and in the lower bars of the frame 75 the carrying rollers b, c'' are cog-wheels upon the shafts of the extreme rollers of the upper series, which engage with the gear wheels d'' upon the line shaft e' by which means the rollers a'' are driven in the manner to be hereinafter described. Any number of the intermediate rollers may be similarly driven which may be deemed necessary to prevent injury from too great tension of the cloth. Immediately over the rollers a'' 80 are placed other rollers f' which press the cloth to the surface of the rollers a'', and as the latter are turned, the cloth is fed back and forth through the machine.

g' is a cog wheel upon the shaft e' which is caused to engage alternately with one or the other of two worm gears h' h'' in the following manner: i' is a metallic frame hinged at k' to the post C'. k'' is a metallic arm in which the frame i' rests, the latter being thrown over into the position seen in Fig. 3 by the spring l''. m² m³ are vertical shafts running in the frame i' and carrying the worm gear h' h''. These shafts are driven by the cords n' n'' from the main driving pulley D'. o' is a shaft suitably boxed in the arm k'' and carrying at its upper extremity a cam p' which bears against the side of the frame i'. This cam is constructed of two segments of circles of different radii, and so arranged that when the segment of longer radius bears against the frame i' it shall cause the worm gear h'' to engage with the wheel g' as in Fig. 1, and when the short radius of the cam p' bears against the frame, the latter is thrown by the spring l'' into the position seen in Fig.

3 in which the wheel g' is driven by the worm h' , and thus as the cam p' revolves, the rollers a'' are driven alternately in one direction and the other. The cam p' is 5 made to revolve slowly while the machine is in operation by a band upon the pulley E' which is driven by a small pulley upon the shaft of the driving pulley D' .

Operation: The cloth is threaded into the 10 machine as seen in Fig. 2. The frame is placed in the vat which receives the requisite quantity of dyeing liquor. The latter should rise at least sufficiently high to cover the lower rollers b . An intermittent rotary 15 motion is then communicated to the rollers a'' as described, by which means the cloth is repeatedly passed through the dyeing liquor. The operation being watched by the attendant, who immediately withdraws the 20 dye liquor or the cloth as he sees the desired color is attained.

The frame may be withdrawn from the vat, or the machinery may be so arranged that the revolution of the cam p' may be interrupted at any moment, in which case the rollers will continue to revolve in one direction and the cloth will be run out of the machine.

It is evident that a variety of methods 30 may be adopted for the purpose of producing the intermittent rotary motion of the rollers. The one above described, however, I have found to be both simple and efficient. There are also other methods of feeding the 35 cloth through the machine which may at times be found useful, for instance, in place of the rollers $a'' f'$, a single roller may be employed at each end of the machine, to which are attached short aprons, to which 40 the ends of the cloth may be stitched, and in this manner the extreme ends of the string of goods will be equally well dyed with any part of it. The exact amount of surface motion to be given to the rollers 45 is not material. In general however it should not be less than double the distance between the upper and lower rollers.

The advantages which my machine possesses over those heretofore in use result 50 from the fact that many colors which cannot be dyed upon the old machines may be applied by it without difficulty, and thus the tedious and expensive process of hand dyeing may be dispensed with. One difficulty with the old machines arises from

the fact that the dye liquor as before stated, becomes sensibly weakened before the cloth has passed once through it, and thus the goods are not uniformly dyed. Another 60 results from the fact that in passing through the vat once in the old machines, the cloth made many dips into the dye liquor or remained for a considerable time immersed in it, and thus it often happened that the shade produced by once running 65 through the machine was not sufficiently intense, while that produced by a second passage was deeper than was required. In both these instances the hand machine has heretofore been resorted to. The difficulties 70 are, however, in each case removed by the employment of my machine, as the whole of the cloth is immersed almost at the same instant, and the operation may be watched as it proceeds, and the cloth or the liquor 75 withdrawn at any instant the desired shade is attained.

I do not intend to limit myself to any particular machinery for the purpose of producing the reciprocating motion of the 80 cloth, as this forms no part of my invention, and a great variety of machinery may be employed for the purpose, which may be actuated either by hand or by other power. And, I do not intend running the 85 cloth through the machine from end to end back and forth as has heretofore been practiced in machine and hand dyeing; but

What I do claim as my invention and desire to secure by Letters Patent is— 90

Communicating to the goods while in the vat a reciprocating motion back and forth of at least double the distance from the upper rollers to the surface of the liquor, so as to insure the immersion of the whole material once for each vibration, by which means I am enabled to give to the whole 95 of the fabric any required number of dips, and to interrupt the operation at the instant the desired shade is attained, as set 100 forth.

In testimony whereof I have hereunto set my signature this thirtieth day of July one thousand eight hundred and fifty-three.

C. T. APPLETON.
